CLAIM

The ornamental design for a security lamp, as shown and described.

DESCRIPTION

FIG. 1 is a front, left-side, top perspective view of the security lamp.

FIG. 2 is a front elevation view thereof.

FIG. 3 is a rear elevation view thereof.

FIG. 4 is a left-side elevation view thereof.

FIG. 5 is a right-side elevation view thereof.

(Continued)

FIG. 6 is a top plan view thereof; and,
 FIG. 7 is a bottom plan view thereof.
 The broken lines depict parts of the security lamp that form
 no part of the claimed design.

1 Claim, 7 Drawing Sheets
